STOP MECHANISM FOR KNITTING MACHINES

Thomas J. Stalsworth, Knoxville, Tenn., assignor of one-fourth to William A. Stalsworth and one-half to Charles F. Clayton, Knoxville, Tenn.

Application October 6, 1939; Serial No. 298,304

8 Claims. (Cl. 66—157)

This invention relates to an improvement in stop motions for knitting machines, particularly for rib knitting machines, such as are used for the knitting of underwear and hosiery, of the type known as cylinder and dial machines.

In the operation of such knitting machines, it is desirable to provide stop mechanism for the machine that will be operative automatically when the knitting mechanism ceases to function in its normal and intended manner, as for instance, if a needle should break, or if the thread breaks or gathers lint thereon that would produce an irregularity in the knitted goods.

Attempts have been made heretofore to provide stop mechanisms for knitting machines, but these have generally been complex in structure, expensive, and usually unsatisfactory.

The object of this invention is to improve the construction of the stop mechanism and to enable it to function in two directions in response either to a break in the thread or to a lump thereon, for controlling the stopping of the machine or signaling such irregularity in the operation. This attachment is small in size, simple in design and construction and consequently inexpensive to manufacture, and is practical in its operation and use to accomplish the desired result.

The invention preferably utilizes an enclosed casing containing a switch arm operating between contacts, the engagement with either of which will serve to close an electric circuit to indicate or control the stopping of the machine. The switch arm is connected with a breaker arm that rides the stitch and controls the switch arm in response to a break in the thread or a lump thereon, thus providing two-way control that will accomplish the desired stopping action automatically in response to different irregularities or conditions in the knitting machine.

The invention is embodied in a preferred form thereof, which is illustrated in the accompanying drawing in which:

Fig. 1 is a partial front elevation of a portion of a knitting machine showing the invention applied thereto;

Fig. 2 is a perspective view of the attachment in its relation to the thread;

Fig. 3 is a vertical sectional view through the attachment; and

Fig. 4 is a horizontal sectional view therethrough on the line 4—4 of Fig. 3.

The invention is shown applied to a knitting machine of the cylinder and dial type in which the frame of the machine is designated generally by the numeral 1 and is provided with the usual

bank of cylinder needles 2 and dial needles 3, constructed and operating in the usual way to form a stitch 4, as shown in Fig. 2. The thread to the needles is passed through thread guides 5.

The attachment for controlling or indicating the stopping of the machine comprises an elongated tubular box 6, preferably constructed of Celluloid or other transparent insulating material, and which box 6 has the side walls thereof sealed together and is closed at the bottom by a cap 7 which extends also over three sides of the box part way along the length thereof, having an out-turned supporting plate 8 that is secured to the frame 1 of the machine just behind the thread guide 5.

The opposite end of the box 6 is enclosed within a U-shaped cap 9 that embraces said end. The cap 9 carries an upstanding terminal post 10, to which a conducting wire 11 is adapted to be attached, which wire leads to an electric circuit that includes a source of electrical supply, such as a six volt battery, and also includes either mechanism for stopping the knitting machine when the circuit is closed or an electrical indicator for producing a signal to warn the operator that the machine must be stopped. The caps 7 and 9 are of electrical conducting material, such as brass or other metal, and the supporting plate 8 serves to ground one side of the attachment to the frame of the machine, the electric circuit mentioned also being grounded thereto.

The sides of the U-shaped cap 9 carry contacts 12 on respective opposite sides of the attachment, which contacts 12 are in the form of screws threaded through the sides of the cap 9 and into opposite sides of the box 6 with the inner ends thereof in spaced relation from each other. Between the contacts 12 is a switch contact arm 13 supported on a cross shaft 14 journaled in the lower end portion of the box 6, whereby the contact arm 13 stands upright in the box with its upper end portion between the contacts 12. A spring 15 is interposed between one side of the contact arm 13 and the adjacent side of the box tending to move the contact arm 13 to the left in Fig. 1.

The shaft 14 carries a laterally and downwardly extending breaker arm 16 which bears upon the stitch 4 between the respective banks of needles, as shown in Fig. 2. The breaker arm 16 normally rides the stitch and when the machine is operating in its normal and intended manner, the attachment is in such position that the breaker arm 16 will hold the switch contact arm 13 in an intermediate position midway between the

- contacts 12 and out of engagement therewith. The breaker arm is preferably formed of wire and may be bent slightly during installation to dispose its point in its proper position for this purpose according to the construction and characteristics of the knitting machine to which it is applied. This breaker arm is preferably formed integral with the shaft 14 and has the contact arm 13 securely mounted thereon rigid therewith.
- 10 As shown in Fig. 3, the arm 13 is electrically connected with the cap 7 through a connection 17 through which the switch arm 13 is grounded to the frame.

With the breaker arm 16 bearing at its end on the stretch between the dial and cylinder needles, if a needle should break the breaker arm will rise or lower according to the needle which breaks, whereby the switch arm 13 will be moved into engagement with one or the other of the contacts 12, closing the circuit through the wire 11 to automatically stop the machine or to indicate the need for the stopping thereof by the operator. If the thread breaks during the operation of the knitting machine and clears a space between the dial and cylinder needles, this will cause the breaker arm 16 to drop down when it reaches this space, swinging the switch arm 13 into engagement with one of the contacts 12 to close the circuit. If lint or a lump of cotton should be gathered on the needles sufficiently to cause bad knitting, it will raise the breaker arm and swing the switch arm in the opposite direction also stopping the machine. Likewise, it functions to stop the machine when there is no thread in the needles and when the cloth is off the needles.

The attachment prevents breakage of the needles and waste by automatically stopping the machine when an irregularity is encountered during the knitting operation, and yet by means of a simple and inexpensive attachment that may be applied readily to a knitting machine.

I claim:

1. In a knitting machine having stitch forming means, the combination of stop mechanism for the machine comprising a support having spaced contacts, a switch arm arranged between the contacts and a breaker arm connected with the switch arm and extending in position to bear upon the stitch.
2. In a knitting machine having stitch forming means, the combination of stop mechanism for the machine comprising a support having a pair of spaced contacts, a switch arm arranged between the contacts and pivotally mounted for swinging movement toward and from the contacts, and a breaker arm fixed to the switch arm and movable therewith, said breaker arm extending in position to bear upon the stitch.
3. In a knitting machine having stitch forming means, the combination of stop mechanism for the machine comprising a support having a pair of spaced contacts connected together and adapted to be connected with one side of an electric stop circuit, a switch arm pivotally mounted on the support and extending between the contacts for swinging movement toward and from the contacts into engagement therewith, said switch arm being adapted to be connected with the opposite side of the electric stop circuit, and
4. In a knitting machine having stitch forming

means, the combination of stop mechanism for the machine comprising a support having a pair of spaced contacts electrically connected together and having means for connection with one side of an electric stop circuit, a switch arm pivotally mounted on the support and extending between the pair of contacts and having means for connection with the opposite side of said electric stop circuit, and a breaker arm fixed to the switch arm and movable therewith, said breaker arm extending laterally from the support and having a free end in position to bear upon the stitch and to actuate the switch arm in response to imperfections in the stitch.

5. In a knitting machine having stitch forming means, the combination of stop mechanism for the machine comprising a support of insulating material having a pair of spaced contacts electrically connected together and having means for connection with one side of an electric stop circuit, a switch arm journaled on the support and extending between the contacts for swinging movement toward and from the same into engagement therewith, resilient means bearing against one side of the switch arm, means for connecting the switch arm with the opposite side of the electric stop circuit, and a breaker arm fixed to the switch arm and extending laterally therefrom in position to bear upon the stitch and hold the switch arm in an intermediate position between the contacts against the tension of the resilient means.

6. In a knitting machine having stitch forming means, the combination of stop mechanism for the machine comprising an elongated tubular support of insulating material having spaced contacts extending in opposite sides thereof, a cap connecting the contacts together and having a binding post thereon for connection with one side of an electric stop circuit, a switch arm journaled in the tubular support and extending between the contacts in position to engage the same, resilient means acting on the switch arm in one direction, means for connecting the switch arm with the opposite side of the electric stop circuit, and a breaker arm secured to the switch arm for moving the same against the tension of the resilient means, said breaker arm extending laterally from the support in position to bear upon the stitch and to move the switch arm in response to irregularities therein.

7. In a knitting machine having stitch forming means, the combination of stop mechanism for the machine comprising an elongated tubular support of insulating material having spaced contacts extending in opposite sides thereof, a cap connecting the contacts together and having a binding post thereon for connection with one side of an electric stop circuit, a switch arm journaled in the tubular support and extending between the contacts in position for swinging movement into engagement therewith, a spring bearing against one side of the switch arm tending to move the same in one direction, a cap secured to the under portion of the support and having a laterally extending supporting plate connected with the switch arm and adapted to be connected with the other side of the electric stop circuit, and a breaker arm secured to the switch arm and extending laterally from the support in position to bear upon the stitch for movement of the switch arm in response to irregularities therein.

8. In a knitting machine having stitch forming means, the combination of stop mechanism for the machine comprising an elongated box of in-

5 sulating material, metallic caps secured over opposite ends of the box with side walls embracing said ends of the box, one of said caps having contacts connected therewith and extending into opposite sides of the box and having a binding post thereon for connection with one side of an electric stop circuit, the other cap having a laterally extending supporting plate adapted to be connected with the opposite side of said electric stop circuit, a switch arm journaled in the box

10

and extending between the pair of contacts in position for movement into engagement therewith, said switch arm being connected with the last-mentioned cap, and a breaker arm secured to the switch arm and extending laterally and downwardly therefrom in position to ride upon the stitch and to move the switch arm in response to irregularities therein.

THOMAS J. STALSWORTH. 10
